[57] CLAIM

The ornamental design for a popover baking pan, substantially as shown and described.

DESCRIPTION

FIG. 1 is a top plan view of a popover baking pan showing my new design;

FIG. 2 is a left side elevational view thereof; the right side being a mirror image thereof;

FIG. 3 is a front elevational view thereof;

FIG. 4 is a bottom plan view thereof; and

FIG. 5 is a fragmentary cross-sectional view taken on line 5—5 of FIG. 1.

FIG. 1

FIG. 2

FIG. 3

FIG. 4

FIG. 5
